US00D808058S

(12) **United States Design Patent** (10) Patent No.: **US D808,058 S**
(45) Date of Patent: **** Jan. 16, 2018**

(54) **DLWNLIGHT**

(71) Applicant: **AURORA LIMITED**, St. Albans (GB)

(72) Inventor: **Andrew Johnson**, St Albans (GB)

(73) Assignee: **Aurora Limited**, Welwyn Garden (GB)

(**) Term: **15 Years**

(21) Appl. No.: **35/501,724**

(22) Filed: **Sep. 16, 2016**

(80) **Hague Agreement Data**

Int. Filing Date: **Aug. 18, 2016**

Int. Reg. No.: **DM/092834**

Int. Reg. Date: **Sep. 16, 2016**

Int. Reg. Pub. Date: **Oct. 14, 2016**

(51) **LOC (11) Cl. 26-05**

(52) **U.S. Cl.**

USPC **D26/74**

(58) **Field of Classification Search**

USPC D26/74; D6/708

CPC .. F21S 6/002; F21S 6/005; F21S 10/00; F21S 6/003; F21S 6/006
